SPLIT RING FITTING MACHINE

Clifford E. Storer, Cleveland, Ohio

Application June 13, 1932, Serial No. 616,781

4 Claims. (Cl. 29—76)

This invention relates to new and useful improvements in split ring fitting machines.

It is the principal object of my invention to provide a simple, compact and efficient device for filing the adjacent free ends of a split ring, such as a piston ring, to make their faces parallel. The device in its different forms is adjustable to accommodate different sized rings, and may be clamped to a bench, or mounted in a vise, for convenient operation. The clamp bar also has graduations on its face to center the various size rings over the cutter.

It is another object of my invention to provide means for adjusting the device to produce square or diagonal cuts on the split ring.

Other important and incidental objects will be brought out in the following specification and particularly set forth in the subjoined claims.

In the accompanying drawings illustrating the different forms of embodiment of my device, Figure 1 is a side view of one type of it, showing the ring to be filed in a vertical position. Figure 2 is an end view thereof. Figure 3 is a top view of the same. Figure 4 is a plan view of the base block showing the locking holes. Figure 5 shows views of the various type of ring joints to be filed by my device. Figure 6 is a top plan view of another form of my filing device. Figure 7 is a side view of the latter. Figure 8 is a top view of one of the gage clamps.

Figure 9 is an end view of the gage clamp shown at Figure 8. Figure 10 is a top view of another type wherein the ring is clamped to the face of the device in a horizontal position. Figure 11 is an end view of the device shown at Figure 10. And Figure 12 is an end view of the same showing the filing disc adjusted to an angular position.

Referring to Figures 1 to 5 inclusive, illustrating one form of embodiment of my invention, the numeral 1 designates a base block formed with a bottom hole to receive the upper end of a supporting rod 2 having a right-angled bottom portion 3. This rod, which is secured to the block 1 by a stud 4, has in its end 3 a vertical screw hole to receive the threaded upper end of an angle clamp 5 by which the base block may be clamped to a bench.

Formed in the upper part of the base block 1 is a transverse hole to receive a shaft 6. Secured to the inner end of the latter is a hub 7 which is rotatable within a bearing recess provided in the inner face of the block 1. Secured to this hub by a stud 8 and washer 9 is a disc file 10 having a cutting surface on each side. To the other end of the shaft 6 there is secured, beyond a sleeve 11 surrounding the shaft, the inverted U-shaped end

12 of a handle 13. The latter is firmly secured to the shaft by a stud 14 which passes downwardly through a hole in the horizontal part of the U-portion of the handle, to engage in a recessed part of the shaft. A lock nut 15 is applied to the stud 14 between the shaft and said horizontal part of the handle.

Adapted to be applied to the top surface of the block 1 is a channel, clamp block 16 formed in its lower surface with a quadrant shaped slot 17 to receive the projecting part of the filing disc 10 in its different adjusted positions.

The channel clamp block 16 is adapted to receive a graduated clamp bar 18 which is laterally adjusted within it by a set screw 19 to firmly clamp the split end of a ring 20 against the outer wall of the channel. The bottom of the channel block 16 is beveled from each end down to the edges of the quadrant-shaped slot 17 to support a split ring in a position to present its adjacent free ends to the filing disc 10 which projects into the slot.

The split ring to be filed is properly centered in the clamp block 16 by two gage seats 21 and 22. These gage seats consist of vertical plates 20 formed with longitudinal slots 23 and top flanges 24 that are free to travel over the top surface of the channel block 16. Projecting inwardly from the top flange on each gage seat, over the graduated end of the clamp bar 18 is an indicating finger 25 formed with a beveled inner edge to engage the split ring inserted in the channel block and provide an adjustable seat for it. The graduations on the ends of the clamp bar will determine the position of the gage seats 21 and 22 to accommodate the size of ring to be filed, said seats being held in their adjusted positions by set screws 26 which are inserted through the slots 23 in them.

When clamped in the block 16 as above described, the split ring, in this instance the ring 20, may have its free ends filed by turning the disc 10 through the handle 13, to provide parallel faces on said ends.

The device is constructed to produce any one of the cuts shown in Figure 5, by mounting the clamp block 16 at the desired angle upon the base block 1. For this purpose, the base block is formed with a plurality of large holes 27 and small holes 28. The small holes are in pairs to receive two pins 29 that project downwardly from the bottom of the clamp block 16, to hold the latter in an adjusted position, being assisted by a set screw 30 which is passed downwardly through one of two holes in said clamp block into

a large hole 27 in the base block. The straight joint 31 in the ring 20 is produced when the clamp block 16 is secured to the base block 1 at a right angle, while the oblique cuts 32 and 33 are produced when the clamp block is secured at an acute angle to the base block.

Referring now to Figures 6 to 9, inclusive, I have shown another embodiment of my invention, the numeral 34 indicating a circular head having a square depending shank 35 by which the device may be mounted in a vise or other suitable bracket.

The head 34 is provided with a center oblong aperture 36 extending downwardly through the shank. Extending laterally from the aperture 36 through the periphery of the head and parallel with its top face 37, is a hole to receive a shaft 38. Where this shaft projects into the aperture 36, it is shouldered to receive a double faced filing disc 39, like the disc file 10, and secured in place by hex nuts 40, 40.

Beyond the periphery of the head the extended end of the shaft 38 is threaded to receive check nuts 41, 41, by which the shaft may be adjusted axially to gage the end play. Also, to the outer end of this shaft a handle 42, similar to the handle 13, is applied.

The top face 37 of the head is provided with a series of equally spaced holes 43 adapted to receive therein depending dowel pins 44, 44 in the bottom surface of a clamp block 45, that is mounted on the head. By means of these pins and the spaced holes, the clamp block 45 in which the rings are held, may be positioned in axial alignment with the shaft 38, or obliquely positioned thereto, as shown by the dotted lines at Figure 6, to file the ring joints shown in Figure 5.

This clamp block 45 is similar to the channel clamp 16 and is provided in its lower face, at its center, with oppositely disposed quadrant slots 46, 46 that receive therein the projecting filing disc 39 in its various adjusted positions.

The top surface of the clamp block 45 has a wide longitudinal channel 47 that is adapted to receive therein a graduated clamp bar 47^a, which is laterally adjusted by a thumb screw 48 to firmly clamp a split ring 20 between it and the opposite wall of the channel. One side of the channel, adjacent the wall opposite the clamp, has therein a narrow accurate ledge 49 to gage the depth to which the ring 20 may be inserted.

In order that the ring may be properly centered over the filing disc 39, I have provided on the top face of the clamp block 45 adjustable gages 50 and 51 that co-act with the ledge 49, the ring engaging the latter and the adjacent beveled faces 52, 53 of the gages 50, 51, respectively.

These gages consist of flat L shaped plates, oppositely disposed as shown at Figure 8, and having in their aligned legs 54 and 55, elongated slots 56 and 57 that receive therethrough thumb screws 58 and 58. These screws are received by threaded holes in the top face of the clamp block 45 and permit an adjustment of the clamps, co-extensive the slots 56 and 57.

The beveled faces 52, 53 of the gages extend over the face of the clamp bar in registry with graduations 59 thereon, whereby when these beveled faces are aligned with like numbers on each side the clamp block will properly receive therein a certain size ring that will also be properly centered over the disc file. When the shaft 6 is rotated the adjacent faces of the ring 20 will be filed in true parallelism to provide a perfect seal when placed in use.

When it is desired to insert a larger or smaller diameter ring 20 in the clamp, these gages are either further separated or moved closer together.

In Figures 10, 11 and 12 I have shown still another embodiment of my invention, wherein the split rings are held in a flat or horizontal position. Referring now to the above figures, the numeral 59 designates a flat base plate having a depending shank 60 by which the device may be mounted in a vise or bracket (not shown). The base plate 59 is substantially square, and has in one corner thereof a recess 61. This recess forms between it and the side of the plate a leg 62.

Positioned in the recess 61 is a swivel block 63 that is rotatable about a threaded stud 64, received therein. This stud extends outwardly through a recess 65 in the leg 62 and through an axial hole 66 in an adjusting block 67. Beyond the block 67 the stud terminates in an enlarged head 68 that receives therethrough a pin 69 by which the stud may be turned.

The block 63 as shown in Figure 10 is substantially L shaped, and receives in a lateral hole through it, a shaft 70. This shaft projects into the recess 61 and has mounted on its threaded shouldered end 71 a double faced filing disc 72, similar to the filing disc 39, and secured to the shaft by a nut 73 and washer 74. To the outer projecting end of the shaft a handle 75, similar to the handle 42, is attached by which the filing disc may be rotated. Lock nuts 75^a are provided to gage the end play of the latter.

The adjusting block 67 has parallel sides 76, 76 that are received by a shallow recess in the outer face of the leg 62 to which it is secured by screws 77, 77, extending through elongated slots 78, 78 in the block 67.

Between the screws 77, 77, and below the stud 64, is a wing screw 79 that also passes through another elongated slot 80 and is received by a threaded hole in the leg 62. When the wing screw 79 is loosened, the block 67 may be adjusted vertically, carrying the swivel block 63 and filing disc 72 with it.

Where the filing disc 72 projects into the recess 61, it enters a lateral recess 81 opposite the side of the leg 62. Below the surface of the plate the sides 81^a of the recess 81 are beveled outwardly at an oblique angle as shown at Figure 11. Now, when it is desired to file the ends of a split ring at the oblique cuts 32 and 33 shown in Figure 5, the wing screw 79 is loosened and the block 67 is raised and again held in place by tightening the wing screw. (See Figure 12). The stud 64 is loosened to permit adjustment of the swivel block and disc file to either of the obliquely inclined positions as shown at Figure 12.

The split ring 20 to be filed is placed upon the plate 59 as shown in Figure 10, with its free ends against the opposite faces of the filing disc 72. In this position the ring 20 engages two oppositely disposed stop pins 82, 83 in the top of the plate and at each side of the recess 81.

The step-cut joint 31^a may also be filed by this device by first filing one side of the cut and then reversing the position of the ring in the band 84 to file the opposite side thereof.

Attached to the stud 83 is one end of a flexible metal band 84 that encircles the periphery of the ring 20 and has its other end attached to a spiral drum 85 by a screw 86 in its periphery.

As shown in Figure 10, this spiral drum is ro-

tatable about a wing screw 87 that passes downwardly through the latter, and a spur gear 88 integral with its lower face, to a threaded hole in the plate 59. Meshing with the gear 88 is 5 another gear 89 rotatable with a stud 90, journaled in the plate 59 and extending upwardly therefrom.

Attached to the top face of the gear 89 is a graduated disc 91, co-acting with a gage 92 secured to the plate 59. The upper end of the stud 90 is provided with a square shank 93 to receive thereon a crank 94 by which the spiral drum may be rotated when the screw 87 is loosened.

15 When a split ring 20 is applied to the face of the plate 59, the band 84 is loosened and the ring inserted within it, with its adjacent end on each side of the filing disc. The spiral drum is now rotated by the crank 94, winding the band 84 20 about its periphery until the latter firmly grips the ring 20, whereupon the screw 87 is tightened to hold the band in its proper contact with the ring. (See Figure 12.)

Because of the spiral contour of the drum, its 25 periphery is constantly projected toward the ring when smaller ones are inserted, thus insuring a maximum contact of the band 84 with the periphery of the ring. When the crank and graduated disc 91 are rotated to the desired tension, a record 30 may be made of the setting relative to the gage 92, so that several rings may be filed to exactness.

When square cuts are filed, the adjusting block is lowered as shown at Figure 11, and when oblique cuts are to be filed the adjusting block is 35 raised and the swivel block rotated as shown in Figure 12. When so rotated, the curved block 63 will contact a stop pin 95, above the stud 64, and projecting inwardly from the block 67.

With either of the ring filing devices that I 40 have described it is possible to quickly and accurately file the adjacent faces of the ring ends to exact parallelism. This is not possible in ordinary operations with a hand file, as commonly done. When a ring filed with my devices is fitted 45 to an object, such as a piston or sliding valve, a perfect seal is effected by the true contact of the split ring faces.

While I have disclosed my device as constructed 50 of cast iron and steel parts, I do not wish to be limited to that specific structure since metal stampings may be substituted to accomplish the same result.

Having described my invention, I claim:

1. In a device of the type described, a base member, a filing disc journaled in said base member, means for rotating said disc, a channel clamping block formed with a slot to receive said disc, for attachment to said base member, a clamping bar laterally adjustable in said channel member to receive between it and the outer wall of the channel block a split ring to present the free ends of the latter to said filing disc, graduations on said clamping bar, and a pair of gage seats adjustable over the graduated clamping bar to center said ring over the filing disc. 80

2. In a device of the type described, a base member, a filing disc journaled in said base member, means for rotating said disc, a channel clamping block formed with a slot to receive said disc, for attachment to said base member, a clamping bar laterally adjustable in said channel member to receive between it and the outer wall of the channel block a split ring to present the free ends of the latter to said filing disc, graduations on said clamping bar, a pair of slotted, flanged plates slidable over said clamping block, and beveled seat extensions on said plates, that project 100 over said graduations, to receive and center the split ring over the filing disc. 85

3. In a device of the type described, a base member, a filing disc journaled in said base member, means for rotating said disc, a clamping 105 block formed with a quadrant shaped slot to receive said disc, the base member formed with large holes, and small holes, arranged in pairs, pins on said clamping block for entrance into the small holes and a set screw carried by said 110 block for entrance into a large hole, to hold said block in different angular positions on the base member, and means for clamping in said block a split ring to present its adjacent free ends in a desired angular position to the filing disc. 115

4. In a device of the type described, a base member, a filing disc journaled in said base member, means for rotating said disc, a channel clamping block formed with a quadrant shaped slot to receive said disc, and means for attaching 120 said block in different angular positions to the base member, the bottom of said channel block being beveled from each end down to the edges of the quadrant-shaped slot to support a split ring in a position to present its free ends to the 125 filing disc which projects upwardly through the slot. 130

CLIFFORD E. STORER.
